UNITED STATES PATENT OFFICE

PACIFIC J. THOMAS, OF PHILADELPHIA, PENNSYLVANIA, ASSIGNOR TO FLETCHER WORKS, INCORPORATED, OF PHILADELPHIA, PENNSYLVANIA, A CORPORATION OF PENNSYLVANIA

BOBBIN HOLDER

Application filed December 17, 1928. Serial No. 326,488.

This invention relates to an improvement in bobbin holders for twisting or spinning machines. In such machines, as now constructed, the yarn is drawn from spools 5 mounted on spindles at the lower part of the machine, passing up over porcelain guides carried by a reciprocating traverse bar and on to bobbins at the top of the machine.

These bobbins are rotated by friction rolls 10 contacting with the yarn on the bobbins, so that the same linear or surface speed is maintained throughout the operation regardless of the size of the bobbin to insure a uniform twist per inch. If a thread breaks, however, 15 in such machines, the bobbin will continue to rotate, driven by the friction roll, until lifted off by hand, and if not lifted off at once this continued rolling or rotating will untwist the yarn thereon for several yards. Further, 20 more, under such conditions the yarn at the surface may become somewhat abraded resulting in second grade stock.

The invention of the present application overcomes this action, means being provided 25 whereby when a thread breaks the bobbin is lifted automatically and bodily away from the friction roll, the mechanism employed being of such a character as to act as a brake to mechanically bring the bobbin to rest.

Not only does this apparatus effect a saving in yarn by avoidance of abrasion as well 30 as untwisting of the yarn, but it eliminates the expense of an operator to watch for breakages. As a matter of fact such operators are not entirely satisfactory inasmuch as the yarn may have broken and the silk be 35 untwisted somewhat before the break is noticed.

With the present construction, therefore, 40 I provide automatically functioning apparatus so arranged that when a yarn breaks the bobbin will be lifted clear of its driving roll, thereby preventing rubbing and abrasion of the yarn, the bobbin also being

brought to rest automatically to prevent untwisting of the yarn.

In the drawings accompanying this application, Fig. 1 is a section transverse of the friction roll, the bobbin and the traverse rail 50 of my invention;

Fig. 2 is a part plan and part sectional view of a portion of a machine in which my invention is incorporated;

Fig. 3 is an elevational view taken from 55 the front of the apparatus, i. e., looking from left to right in Fig. 1;

Fig. 4 is a view somewhat similar to Fig. 1 but showing various parts of the apparatus in the positions they assume when a thread 60 breaks.

Referring to the drawings in detail, I designate the friction driving rollers, it being understood that in an actual machine there will be a number of these rollers all suitably 65 driven and all disposed on the one shaft as is now commercial practice.

The bobbins, of which there is one for each friction roller, are designated 2. There is a bobbin disposed above each friction roller 70 and the silk or other material being spun or twisted rests on the periphery of the friction roller, thereby to provide a drive between the friction driving rollers and bobbins. The mechanism so far described is standard construction.

Each bobbin is mounted in a frame designated 3 rigidly secured to a rail 4 extending lengthwise of the machine.

I have mentioned above that in existing machines the thread being twisted or spun is taken from spools mounted on spindles disposed below the bobbins, and that in passing to the bobbins the thread is led through a porcelain guide. Such a guide is shown at 5 in Fig. 1. Heretofore the difficulty experienced with these machines has been due to breaking of the thread. The thread is designated 6 and in machines as heretofore constructed when a thread breaks the bobbin or 85

rather the material thereon remaining in contact with the friction roller will continue to rotate with the likelihood of abrasion of the surface of the silk or other material on the bobbin and untwisting of this material. The result is a second grade product. In view of all this it becomes necessary to employ attendants to watch for broken threads, which is only partially satisfactory as the attendant will not always see a thread at the instant it is broken, with the result that despite the precautions taken against it a second grade product results.

The porcelain guide 5 which I have referred to above is carried by a traverse rail designated 8, this rail being reciprocated through suitable mechanism, standard equipment in existing machines, over rollers 9, to properly lead or guide the thread to the bobbin.

In the present arrangement the frame 3 above referred to provides bearings 10 and 11 for the bobbins. This frame is provided with a cradle 12 pivoted thereto. The ends 25 or end members of this cradle which I shall designate 13 lie beneath the end members 14 of each bobbin. The pivot for each cradle is designated 15 and is provided with a coil spring 12' so arranged that this spring will 30 tend to raise the cradle from the position shown in Fig. 1 to that shown in Fig. 4.

Means, however, in the form of a latch are provided for holding the cradle in depressed position, that is to say in the position shown 35 in Fig. 1, at which time the bobbin 2 lies in its normal position in its bearing in the frame 3 with the cradle end members 13 out of contact with the bobbin ends but beneath the same. This latch mechanism may be in the 40 nature of a flat spring 16 secured at 17 to the end of the frame 3. This spring latch is provided with a lateral projection 18 extending toward the cradle which is adapted to co-operate with a projection 19 on the cradle, 45 so that when the cradle is in depressed position, i. e., in the position of Fig. 1, the member 19 will lie below the member 18 and be held thereby in this position against the action of the spring 12'.

To trip the latch mechanism so as to permit the cradle automatically to lift thereby to engage and raise the bobbin, I provide the spring latch 16 with a tripping finger 22. Depression of this finger will move the member 18 out of the path of the projection 19 on the cradle and the cradle will be raised automatically by the spring 12' to raise the bobbin as will be presently described in connection with the breaking of the thread 6.

I have already mentioned that the traverse bar 8 carries a porcelain guide 5 for the thread. It also carries a guide 23 which may be of porcelain or any other suitable smooth material which will not damage the surface 65 of the thread being twisted or spun, this mem-

ber being pivoted at 24 to the mount which carries the guide 5 and all of which is secured to the traverse rail 8. This guide 23, or possibly more accurately, this tripper carries an extension or arm 25 adapted when a thread breaks to engage the trip 22 of the latch mechanism to depress and release the same, that is to move the projection 18 of the spring latch out beyond the projection 19 on the cradle to permit the cradle to lift automatically from the position of Fig. 1 to the position shown in Fig. 4, carrying with it the bobbin 2. Inasmuch as the cradle when being lifted engages the end members 14 of the bobbin, the cradle will act as a brake on the bobbin, so that not only is the bobbin lifted to bring the material thereon out of engagement with the driving friction roller 1, but in effect a brake is applied to bring the bobbin to rest. Consequently the material on the bobbin cannot be abraded by the friction roller and the silk or other material on the bobbin cannot be untwisted due to continued rotation of the bobbin out of engagement with the roller 1 with the thread 6 broken.

In a machine where several bobbins arranged as described are provided, as will be the commercial application of my invention, it may be desirable to provide for holding the members 25 out of engagement with the projections 22 on the spring latches 16 manually, when starting the machine inasmuch as at that time there is no tension on the threads 6.

I have provided, therefore, a lug 26 at each bobbin and operable by a rod or wire 28 from one end of the machine, these lugs being of such a character as to be movable manually when desired into the path of the lugs 25. This will insure in starting off the machine that the members 25 will be maintained out of engagement with the trip fingers 22, so that the cradles will all be in their depressed and latched position with the bobbins properly located in their respective bearings. Of course after the machine has begun to operate so that there is tension on the threads 6 then the lugs 26 will be withdrawn and the members 25 will be held by the tension in the respective threads out of engagement 115 with the trip fingers 22 except when a thread is broken, whereupon the guide 23 will drop down and bring the member 25 into position to engage the trip member 22 forcing the same downwardly, releasing the cradle at that particular bobbin and allowing the same to move upwardly automatically under the action of the spring 12' to raise the bobbin and the material thereon.

I have provided, therefore, for a stop motion trip mounted on the traverse bar, controlled by the tension in the thread being twisted or spun and operable automatically upon the breaking of a thread in the machine; for the lifting of the bobbin, at a 120

broken thread, free of the driving roller; and for a brake action on the bobbin after the same is raised.

It is to be understood that changes may be made in the construction herein illustrated and described within the purview of my invention.

What I claim is:—

1. In a thread twisting or spinning machine the combination of a bobbin, a frame providing bearings therefor and in which the bobbin is rotated, a pivoted cradle mounted beneath the bobbin, a spring for moving the cradle about its pivot to raise the bobbin out of its bearings and means controlled by the thread being led to the bobbin to release the cradle under predetermined conditions to permit the same to move to its raised position.

2. In a thread twisting or spinning machine a frame, a bobbin mounted in bearings therein, a pivoted cradle extending beneath the bobbin, a spring for moving the cradle into engagement with the bobbin and to raise the bobbin out of its bearings in said frame, and latch mechanism controlled by the thread being twisted or spun for normally holding the cradle out of bobbin-engaging position, said means being operable upon the breakage of the thread to release said latch mechanism whereby the bobbin is raised out of its bearings.

3. In a twisting or spinning machine the combination of a frame, a bobbin mounted in bearings thereon, a pivoted cradle beneath the bobbin and normally out of contact therewith, a traverse bar extending longitudinally of the bobbin and stop motion tripping mechanism mounted on said traverse bar and operating with said cradle to release the same under predetermined conditions, whereby the cradle pivots toward the bobbin into engagement with the same to move the bobbin out of its bearings.

4. In a twisting or spinning machine a bobbin frame, a bobbin mounted therein, a friction roller beneath the bobbin adapted to engage the material on the bobbin to drive the same, a cradle pivoted on said frame and extending beneath the bobbin, a spring for moving the cradle into engagement with the bobbin and to thereby raise the thread on the bobbin free of the periphery of the friction roller, a latch for holding the cradle in depressed position and thread-controlled trip mechanism for releasing said latch under predetermined conditions to permit the cradle to move the bobbin away from the friction roller.

5. In a thread twisting or spinning machine a bobbin frame providing bobbin bearings, a cradle pivoted to said frame and underlying a bobbin when mounted in said bearings, means for actuating the cradle toward and into contact with the bobbin un-

der predetermined conditions, latch mechanism normally preventing such movement of the cradle and thread-controlled trip mechanism for releasing said latch.

6. In a thread twisting or spinning machine a bobbin frame, a cradle pivoted thereto, a spring for raising the cradle to lift a bobbin mounted in said frame, latch mechanism for retaining the cradle in depressed position, trip mechanism for releasing said latch mechanism, said cradle upon upward movement applying a braking action to the bobbin.

7. In a thread twisting or spinning machine the combination of a bobbin frame, a bobbin mounted therein, a friction roller positioned adjacent the bobbin and adapted to engage the material on the bobbin to drive the bobbin, a pivoted cradle extending beneath the bobbin, a spring for moving said cradle about its pivot toward the bobbin, latch mechanism for holding the cradle normally in depressed position, and thread-controlled trip mechanism for releasing said latch, said cradle on its upward movement raising the bobbin out of driving engagement with the friction roller and at the same time applying a braking action to the bobbin.

8. In a thread twisting or spinning machine the combination of a bobbin frame, a bobbin mounted therein, a cradle pivoted to said frame and extending beneath the bobbin, a friction roller, the periphery of which is adapted to engage thread upon the bobbin to rotate the bobbin, a reciprocating traverse bar extending lengthwise of the bobbin, a thread-controlled pivoted member carried by said traverse bar, latch mechanism for holding the cradle normally out of bobbin-engaging position, said thread-controlled member being provided with an extension for tripping said latch mechanism upon the breakage of the thread being twisted or spun to unlatch the cradle to permit the same to raise the bobbin from driving engagement with the friction roller.

9. In a twisting or spinning machine a fixed bobbin frame, bobbin bearings therein, a pivoted cradle below said bearings, a spring for moving said cradle toward said bearings and into contact with the bobbin to raise the same out of its bearings, and thread-controlled latch mechanism for normally retaining the cradle in depressed position and operable upon breakage of the thread being twisted or spun to release said latch.

10. In a twisting or spinning machine the combination of a plurality of fixed bobbin frames, a pivoted cradle for each frame, a spring for each cradle adapted to actuate the cradles into engagement with the bobbins to raise the same out of said frames upon thread breakage, latching mechanism for holding said cradles normally in depressed position, thread-controlled means for releasing said

latch mechanism, and manually operable means for holding said latch releasing or tripping mechanism out of operative position in the initial starting of the machine.

- 5 11. In a thread twisting or spinning machine a bobbin, a frame providing bearings for the bobbin, and a pivoted cradle extending beneath the bobbin and normally out of contact therewith and automatically movable about its pivot to engage the bobbin and raise the same out of its bearings upon the breakage of a thread being led to the bobbin.
